UNITED STATES PATENT OFFICE.

ANDREW DODS, OF MIMICO, ONTARIO, CANADA.

VOUSSOIRS FOR THE CONSTRUCTION OF CIRCULAR AND ARCHED MASONRY.

1,269,065.

Specification of Letters Patent. Patented June 11, 1918.

Application filed January 10, 1917. Serial No. 141,673.

To all whom it may concern:

Be it known that I, ANDREW Dods, of the village of Mimico, in the county of York and Province of Ontario, Dominion of Canada, have invented certain new and useful Improvements in Voussoirs for the Construction of Circular and Arched Masonry; and I hereby declare that the following is a full, clear, and exact description of the same.

10 My invention relates to circular and arched masonry, constructed of voussoirs, which may be either solid or hollow blocks, bricks or stones, the terms circular and arch, in their widest signification being commonly understood to mean almost anything of a curved shape employed for the purpose of bearing weight or resisting pressure, but in a more restricted and mechanical sense, being defined as a collection of truncated 15 wedge-shaped bodies, held in position by mutual pressure, and the adhesion of the mortar and cement interposed between them.

The object of my present invention therefore is to so construct the voussoirs that a state of equipollence will be established 25 around the circumference of the structure or the arc thereof, and an inter-locking condition will be created to resist the internal and external pressure thereon, the formation of 30 the inter-locking joints being such as to prevent the dislodgment of the mortar or cement during the erection of the structure, and to set up a wedging or expansive action in a circumferential direction when the 35 pressure is thereon.

With this object in view two sets of alternately arranged voussoirs are employed, one of which for convenience may be termed, the key, and the other, the locking voussoirs.

40 Each key voussoir consists of an arc shaped segment, either solid or hollow and glazed or unglazed, as the case may be, to meet the requirements of the structure and the ideas of the builder, and has zig-zag or staggered 45 sides.

Each locking voussoir consists of an arc shaped segment of corresponding character to, but substantially the invert of, the key voussoir, and has zig-zag or staggered sides 50 to abut against and interlock with the corresponding sides of the adjacent key voussoirs.

This formation of the sides of the key and locking voussoirs is such as to provide for 55 the lodgment of the mortar or cement interposed between them, prevent it running

out of the joints during the erection of the masonry, and operate, by the expansive action of the traverses of the zig-zags to resist the radial separation of the voussoirs during 60 the erection of the masonry and tend to increase the mutual pressure of the voussoirs when subjected to internal or external pressure, and when used in sewer, conduit and tunnel construction, present a minimum of 65 direct connection for seepage through the joints to or from the surrounding soil, the voussoirs being preferably made hollow from salt glazed vitrified clay, similar to that used in the manufacture of circular salt glazed 70 vitrified sewer pipe.

For an understanding of the invention, reference is to be had to the following description and to the accompanying drawings, in which Figure 1 is a vertical section 75 of a circular sewer, conduit or, tunnel constructed in accordance with this invention. Fig. 2 is a sectional detail view of one of the key voussoirs. Fig. 2^a is a side elevation of the same. Fig. 3 is a sectional detail view 80 of one of the locking voussoirs. Fig. 3^a is a side elevation of the construction shown in Fig. 3. Fig. 4 is a longitudinal sectional detail view of a branch voussoir. Fig. 5 is a section taken at right angles to Fig. 4, 85 and Fig. 6 is a plan view from the interior surface of the voussoir shown in Fig. 4.

In the accompanying drawings each voussoir *a* is shown to be of a hollow formation with the arc of its interior wall *a'* concentric 90 with that of its exterior wall *a''*, these walls being braced by a stay *a³* radial to the center of the structure, and joined by zig-zag or staggered sides *a⁴*, the chord of the exterior wall *a''* being greater than the chord of the 95 interior wall.

Each voussoir *b* is of a hollow formation with the arc of its interior wall *b'* concentric with that of its exterior wall *b''*, these walls being braced by a stay *b³* radial to 100 the center of the structure, and joined by zig-zag or staggered sides *b⁴*, the chord of the interior wall being greater than that of the exterior wall, the zig-zag or staggered formation of these sides corresponding to 105 that of the voussoir *a* so that when assembled the traverses of the zig-zags of each voussoir *b* will abut against the corresponding traverses of the zig-zags of the adjacent voussoirs *a*, each of these formations providing a truncated wedge shaped segment, one being substantially the invert 110

of the other, and when hollow combining a minimum of weight and a maximum of strength, and if vitrified eliminating the possibility of seepage and absorption either 5 internally or externally through the voussoirs which is most essential in masonry construction employed for sewer, conduit and tunnel purposes.

As shown in Figs. 1, 2 and 5, the zig-zag 10 sides a^4 each consists of two parallel traverses a^5 and a^6 at the inner and outer extremities respectively of said sides, and diverging from the radius of the segment, which is indicated in these views by the stay 15 a^3 , and a diagonal traverse a^7 converging toward the radius and connecting the traverses a^5 , a^6 . As shown in the drawings the traverses a^5 , form with the outer arc of the segment angles of about sixty degrees, the 20 traverses a^6 form with the inner arc of the segment similar angles, and the traverse a^7 is at substantially right angles to the traverses a^5 , a^6 , but these angles may be varied at will. As shown in Figs. 1 and 3 the zig- 25 zag sides b^4 each consists of three traverses, b^5 , b^6 and b^7 , corresponding to, and in parallelism with the traverses a^5 , a^6 and a^7 of the voussoirs a , the direction of the traverses b^5 , b^6 , b^7 being the invert of the traverses 30 a^5 , a^6 , a^7 respectively and abutting against the same when assembled. The formation of the traverses a^5 , b^5 , and a^6 , b^6 , creates dovetail joints at the inner and outer circumference of the segments and not only 35 prevents the internal and external pressure on the structure from causing the radial displacement of any or all of the voussoirs, but enables such pressure to increase the mutual pressure of the voussoirs against 40 each other until a state of equilibrium exists, the purpose of the mortar, it might be explained, being not so much to maintain the voussoirs in their assembled relation in the structure as to prevent a seepage 45 through the joints either from the exterior or interior of the masonry when erected, as the formation of the joints establishes a perfect lock radially between the parts under

normal conditions and increases the holding 50 tendency of the lock under pressure.

When the voussoirs are employed as casings for columns or in the construction of arches for engineering or architectural work it may not be necessary to vitrify them, but it may be necessary for engineering purposes to make them solid instead of hollow. Therefore, it is not desirous to confine the 55 invention to either the vitrified or hollow construction.

What I claim, however, as new and desire to secure by Letters Patent is—

A sewer construction comprising two sets of voussoirs in which all of the voussoirs of the same set are of the same size and shape but differ in size and shape from those of the other set, and the voussoirs of each set alternately interlock with those of the other set; each voussoir of one set comprising an arched wedge-shaped segment, having zig-zag sides, each side consisting of two parallel traverses located at the inner and outer extremities of the side, diverging from the radius of the voussoir and unequal in length, and a diagonal traverse connecting the inner extremities of the diverging traverses, each voussoir of the other set having zig-zag sides each consisting of two parallel traverses located at the inner and outer extremities of the side and converging toward the radius of the voussoir, and a diagonal traverse connecting the inner extremities of the converging traverses, the lengths and angles of said parallel and diagonal traverses corresponding with those of the other voussoir, the angles of the traverses with respect to their radii being such as to create an interlocking condition which will resist the radial separation of the voussoir when subjected to internal and external pressure.

Toronto, Ontario, December 18th, 1916.

ANDREW DODS.
